US00D900839S

(12) **United States Design Patent** (10) Patent No.: **US D900,839 S**
(45) Date of Patent: **** Nov. 3, 2020**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Cedric Kiefer**, Berlin (DE); **Henryk
Wollik**, Berlin (DE); **Jae Julien**, Seoul
(KR); **Dae-Wung Kim**, Seoul (KR);
Jang-Won Seo, Seoul (KR); **Ji-Hyun
Lee**, Seoul (KR); **Bo-La Lee**, Seoul
(KR)

(73) Assignee: **SAMSUNG ELECTRONICS CO.,
LTD.**, Suwon-si (KR)

(**) Term: **15 Years**

(21) Appl. No.: **29/654,869**

(22) Filed: **Jun. 28, 2018**

(30) **Foreign Application Priority Data**

Jan. 5, 2018 (KR) 30-2018-0000999

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter illustrated by dashed broken lines in the FIGURE illustrates a display screen or portion thereof and forms no part of the claimed design.

1 Claim, 1 Drawing Sheet
